Assignee to

G. F. Filley of St Louis, Mo.

Letter Patent No. 821, (Dated Aug. 5th 1856.

The schedule referred to in these Letters Patent and making part of the same.

To all whom it may concern:

Be it known that I, N. S. Bedder of Troy in the County of Rensselaer, and State of New York, have invented or produced a new and original design for Stove plates, and I do hereby declare that the following is a full, clear and exact description of the same, reference being had to the annexed drawings making part of this

Des. 821

specification:

The description of my design for stove plates is as follows.

Fig. 1, is the top plate with the moulding (a).

Fig. 2, is the bottom plate with the moulding (b).

Fig. 3, is the side plate, with the ornamental pilasters (c)

at each side, and the ornaments (d) upon the panel

Fig. 4, is the end plate decorated with the mouldings (e)

(f), at top and bottom, and the ornament (g) upon the panel.

Fig. 5, shows the curvature of the end plate.

Having fully described my design for stove plates, what I claim as new therein and desire to secure by letters patent, is; the ornamental design and configuration of stove plates, such as herein described and shown in the annexed drawings.
